UNITED STATES PATENT OFFICE.

RICHARD KANN, OF JENA, GERMANY.

ELECTRICALLY-CONTROLLED COIN-FEEDING APPLIANCE FOR VENDING-MACHINES.

SPECIFICATION forming part of Letters Patent No. 659,533, dated October 9, 1900.

Application filed March 8, 1900. Serial No. 7,838. (No model.)

To all whom it may concern:

Be it known that I, RICHARD KANN, a subject of the King of Prussia, Emperor of Germany, residing at Jena-on-the-Saale, in the 5 German Empire, have invented certain new and useful Improvements in Electrically-Controlled Coin-Feeding Appliances for Vending-Machines; and I do hereby declare the following to be a full, clear, and exact description 10 of the invention, such as will enable others skilled in the art to which it appertains to make and use the same, reference being had to the accompanying drawings, and to letters and figures of reference marked thereon, 15 which form a part of this specification.

This invention relates to vending-machines, and more particularly to appliances for controlling the passage of the coin from the guide or chute to the mechanism which controls the 20 delivery of the merchandise vended.

One of the objects of this invention lies in the arrangement of an electrically and mechanically controlled cut-off device at the coin-exit of the coin-receiving guide or chute 25 and means whereby the coin reaching such exit will close an electric circuit including an electromagnet whose armature is adapted to move the cut-off to clear the exit and allow the coin to pass farther into the machine, and 30 in combination therewith means whereby the electric circuit is immediately reclosed after having been opened by the coin moving away from the closing-contacts to prevent the cut-off from being immediately returned to a normal 35 position by the mechanical appliance, as a spring, on such opening of the circuit and the liability of the coin being jammed in the exit of the coin-guide by said cut-off, means being provided for opening the circuit through 40 the agency of the coin after it is moved out of reach of the cut-off device.

A further object of my invention lies in the arrangement of a plurality of coin-receiving guides or chutes either for the reception 45 of coins of uniform or of different values and in the provision of means whereby the electric circuit through the electromagnet is only then closed when a coin has been introduced into each of said guides or chutes, and the 50 combination therewith of appliances whereby the electric appliances which control the opening of the coin-exits in the coin-guides may

be rendered inoperative, so that a machine having a plurality of such receiving guides or chutes may be used for vending articles of 55 different values. Thus, for instance, in a machine having a plurality of coin-receiving guides one or more of which are destined for the reception of coins of a given value and others for the reception of coins of different 60 value, merchandise may be vended of the aggregate value of the coins to be introduced into all of the guides or of the value of the coin to be introduced into one or more of said guides, as will hereinafter appear. 65

That my invention may be fully understood, I will describe the same in detail, reference being had to the accompanying drawings, in which—

Figures 1 and 2 are vertical sectional views, 70 taken at right angles to each other, of so much of a coin-controlled vending machine as will be necessary to illustrate my invention; and Fig. 3 is a diagrammatic view illustrating electrically - controlled coin - feeding appliances in which I have shown an arrangement of seven coin-receiving guides or chutes and appliances, whereby one or more or all but one of the coin-controlled circuit-closers may be cut out of the electric circuits for purposes 75 above stated.

The first object of my invention I attain by the means illustrated in Fig. 1, wherein *a* indicates a coin-guide provided with a coin-exit slot normally closed by a cut-off slide *t*, on 80 the upper face of which is an electric contact *e*, normally in register with the aforesaid exit-slot in guide *a*, which has a slot diametrically opposite said exit-slot, into which projects a spring-contact *b* on a conductive lever *l*', fulcrumed to the guide *a*. The free end of said lever is forked and engages a stud or pin *p* below its head and has bearing on a spring coiled on said stud, whereby the tension of spring *b* may be regulated. A coin *d*, (shown 95 in dotted lines,) introduced into guide *a*, will roll along the same, and its progress will be arrested by the spring *b* and contact *e*, and so held above the exit-slot in said guide, said contacts constituting terminals of an electric 100 circuit presently to be described. Below the cut-off slide and in line with the exit-slot in the coin-guide *a* is arranged a coin-delivery guide or chute *m*, and below the coin-exit

thereof a circuit-breaker *g*. The cut-off slide *t* is secured to one arm of a lever *l*, to the other arm of which is secured the armature *k* of an electromagnet *i*. The lever *l*', carrying contact-spring *b*, is connected through wires 3 4 with one terminal of the electromagnet *i*, the other terminal being connected with the contact *f* of the circuit-breaker *g* through wire 5. The lever *g* is connected by wire 7 with one pole of battery *h*, whose other pole is connected by wires 1 2 with the armature-lever *l*, which is of a conductive material, and at a proper distance from said lever in the direction of its motion under the action of its armature *k* is arranged a contact *n*, connected by wire 8 with wires 3 4.

A coin *d*, dropped into guide *a*, will roll between spring *b* and contact *e* on slide *t*, closing the battery-circuit, current flowing therefrom through wires 1 2, armature-lever *l*, contact *e* on slide *t*, through said coin *d*, and via spring *b*, wires 3 4, electromagnet *i*, wire 5, contacts *f* *g*, and wires 7 to the opposite pole of the battery *h*, the electromagnet *i* is energized, the armature attracted, and the slide moved through armature-lever *l* to uncover the coin-exit slot in guide *a*. As this takes place contact between *e* on slide *t* and said coin is interrupted, thereby interrupting the electric circuit, and without provision to prevent this the slide *t* would immediately be retracted by its spring *o* and might jam the coin in said exit-slot before such coin can drop through it and past the slide, and thereby nullify the operation of the machine; but as the slide *t* is moved by the armature-lever *l* to uncover the aforesaid coin-exit slot, said lever being included in the battery-circuit 1 through branch 2 coming in contact with *n*, immediately recloses said circuit, current flowing then from one pole of battery *h* via 1 2, *l*, *n*, 8 4, electromagnet *i*, 5, *f*, *g*, 6 7 to the opposite pole of said battery *h*, thus maintaining the circuit closed and the electromagnet energized and allowing the coin *d* to drop into coin-delivery chute *m*. As said coin leaves the chute *m* it drops onto the arm *g*' of circuit-breaker *g*, thereby moving the same out of contact with *f* and opening the electric circuit. The electromagnet being demagnetized its armature *k* is released, allowing the spring *o* to move the slide *t* back to its normal position, the lever *l* moving out of contact with *n*, thus placing the parts ready for the reception of another coin.

The second object of my invention I attain by the arrangement shown in Figs. 2 and 3.

In Fig. 2 I have shown my invention in its application to a vending-machine having three coin-receiving guides *a*, *a*', and *a*'', arranged in a line, and below said guides is arranged the cut-off slide *t*, having two coin-slots and three contacts *e* *e*' *e*'' so arranged that when slide *t* is in a normal position its contacts will be in register with the coin-exit slots in the respective guides, as shown, so that a movement of the slide under the

action of lever *l* will move said contacts out of register with said exit-slots, uncover the slot in guide *a*, and bring the slide-slots into register with the exit-slots in guides *a*' *a*'', as will be readily seen from the drawings. With the contacts *e* *e*' *e*'' coöperate spring-contacts *b* *b*' *b*'', as hereinbefore described, to retain the coins and close the electric circuit, and below the slide is a coin-delivery guide or chute having a hopper-top common to all three coin-receiving guides. The electric circuits are substantially as hereinabove described in respect of Fig. 1; but if the machine is used for dispensing goods the value of which requires the introduction of a coin into each of the three guides provision must be made to effect the closure of the electric circuit only when a coin is held between each pair of contacts. Furthermore, it is advantageous that a machine of this kind should be so organized that it may operate with one or two or all three guides. These results I attain as follows: A switch-lever *x*, adapted to be moved to one or the other of three contacts *r* *r*' *r*'', is connected by wires 13 16 1 with one pole of battery *h*, the other pole of which is connected by wire 7 to the circuit-opener lever *g* and through contact-spring *f* and wire 5 with one terminal of the electromagnet *i*, the other terminal of said magnet being connected through wires 4 9 8 with the contact *n*. The spring-contact *b* of guide *a* is included through wire 10 in the electromagnet-circuit 9 4, the slide-contact *e* is connected by wire 11 with spring-contact *b*' of guide *a*', and the slide-contact *e*' is connected by wire 12 with spring-contact *b*'' of guide *a*'', while slide-contact *e*'' is included in the battery-circuit 13 16 1 through wire 3, and lever *l* is included in the same circuit through branch wire 2, as hereinbefore set forth, *o* indicating the retracting-spring for said lever. Finally, wires 11 and 12 are connected by wires 14 15, respectively, with switch-contacts *r* and *r*'. If the operation of the apparatus is to be conditioned upon the dropping of a coin (shown in dotted lines and indicated by *d* *d*' *d*'' into each of the guides *a* *a*' *a*'' the switch-lever *x* is placed on insulation *r*'', thereby switching contacts *r* *r*' out of the circuit. As soon as a coin is held between the slide and spring contacts of each coin-guide current flows as follows: from battery *h* via 1 16 3, *e*'', coin *d*'', contact *b*'', wire 12, contact *e*', coin *d*', spring *b*', wire 11, contact *e*, coin *d*, spring *b*, wires 10 4, electromagnet *i*, wire 5, contact *f*, circuit-breaker *g*, and wires 6 7 to the opposite pole of said battery, the electromagnet *i* is energized, the slide moved to allow the coins in the guides *a* *a*' *a*'' to drop into delivery-chute *m*, and at the same time lever *l* contacts with *n*, thereby reclosing the circuit opened by the coins *d* *d*' *d*'' moving out of contact with their respective spring and slide contacts, current then flowing from battery *h* through wires 1 2, contact *n*, wires 9 4, electromagnet *i*, wire 5, contact *f*, circuit-

breaker g , wires 6 7, back to battery h . Inasmuch as the spring and slide contacts are included in the main electric circuit in series, it is obvious that if a coin were dropped into one of the guides only or into two of said guides the electric circuit would not be closed, because if no coin were in guide a^2 the circuit would be broken at that point, and so also if there were no coin in either of the guides 10 a a' , but one in guide a^2 , as will be readily understood. If only two or only one of the coin-guides a a' a^2 is to be used, the entrance to those or to that guide not in use will be closed by any desired means, so as to avoid 15 loss to the public. When one of the coin-guides only is used—say guide a —the switch-lever x is placed on contact r , the circuit being then closed as follows: battery h , wires 1 16 13, x , r , 14 11, e , coin d , spring b , wires 20 9 4, electromagnet i , wire 5, contact f , lever g , wires 6 7, back to battery, the circuit being maintained closed, as before described, until 20 opened by the action of the coin dropping from chute m onto arm g' of lever g . If, on the other hand, lever x is placed on contact 25 r' , guides a and a' are in use and it will be necessary to drop a coin into each to close the circuit, current then flowing from battery h via 1 16 13, x , r' , 15 12, e' , coin d' , b' , 11, e , 30 coin d , b , 10 4, i , 5, f , g , 6 7, and back to battery. The number of coin-receiving guides may be increased and at the same time means provided whereby one or more or all of said 35 guides may be utilized.

35 In Fig. 3 I have shown, diagrammatically, an arrangement of seven guides. The arrangement may, for instance, be such that guide a should be for the reception of five-cent pieces, guides a' a^2 a^3 a^4 each for the reception of ten-cent pieces, guide a^5 for the reception of fifty-cent pieces, and guide a^6 for the reception of one-dollar pieces, the aggregate amount equaling one dollar and ninety-five cents, so that the apparatus can be used 40 for vending merchandise either of the said aggregate value or of a value of five cents or multiples thereof up to the aggregate value. Instead of arranging one of a pair of terminal contacts on the cut-off slide t and the other 45 above said contacts may be arranged in pairs above the slide, so as to be closed by a coin arrested by the spring-contact of a pair, as shown in Fig. 3, whereby the electrical connections are materially simplified. In said 50 Fig. 3 the same symbols of reference are used to indicate like parts described in reference to Figs. 1 and 2, said symbols being provided with suitable affixes, a single cut-off slide t and a coin-delivery chute common to all the 55 coin-receiving guides and of course a single electromagnet for moving the slide in one direction being used, together with a single battery h .

In order to adapt the apparatus for use 60 with one or more or all of the coin-guides, suitable switches are provided, as will presently appear.

The contacts e to e^6 , inclusive, are respectively connected by wires 10 to 15, inclusive, with the spring-contacts b to b^6 , inclusive, of 70 adjacent coin-guides. Thus e of guide a is connected with b' of guide a' by wire 10, e' of guide a' is connected by wire 11 with b^2 of guide a^2 , and so on throughout the series of contacts. Spring-contacts b to b^6 are respectively connected by wires 20 to 26 with contacts G H I K L M N, controlled by a switch-lever X , connected by wire 1 with one pole of battery h , while contacts e to e^6 are respectively connected through wires 30 to 36 with 75 contacts P, Q, R, S, T, U, and V, controlled by a switch-lever Z , connected through wires 3 4 and branch wire 6, respectively, with one terminal of electromagnet i and with the contact n , hereinbefore described, the other terminal of said electromagnet being connected with the other pole of said battery h through wire 5. The armature-lever l is included in the battery-circuit through wire 7, circuit-breaker f , and branch 8, connected with wire 80 85 90 1. Contact e of guide a is connected by wire 2 with a switch-lever W , which lies normally on an insulation A and is adapted to be moved into contact with contacts B, C, D, E, and F, respectively connected through 95 wires 42 to 46 with the contacts I K L M N of the series controlled by switch-lever X , above referred to. There is a fourth switch Y normally on an insulation s and adapted to be moved into contact with a contact O. Lever 10 Y through branch 28 is included in the circuit 26 of the spring-contact b^6 and contacts N F, while contact O through branch 27 is included in the circuit 25 of spring-contact 105 b^5 and contacts M E, whereby both circuits 25 and 26 can be directly connected through said switch Y.

If, for instance, coin-guide a only is to be made use of, switch X is placed on G and switch Z on V, switches W Y remaining in 110 their normal positions on A s , respectively. A five-cent piece being introduced into guide a , spring-contact b will close upon contact e and current will flow from battery h via 1, X, G, 20, b , e , 30, V, Z, 3 4, electromagnet i , 5, 115 and back to battery. At the same time the slide t will be moved by armature-lever l into contact with n for purposes hereinbefore set forth, current then flowing from battery h via 1 8, g , f , 7, l , n , 6, and 4 to electromagnet i and back to battery via 5. If the guide 120 a' only is to be used, switch X will be on II, while switch Z is placed on U. A ten-cent piece being introduced into coin-guide a' , the spring b' will close upon contact e' and current will flow from battery h via 1 X H 21 b' 125 e' 31 U Z 3 4 i 5 back to battery, the circuit being maintained open, as before described. If guides a and a' are to be used, switch X is on G and switch Z on U. A five-cent piece 130 introduced into guide a and a ten-cent piece into guide a' closes their respective contacts b e and b' e' , current flowing from battery h via 1 X G 20 b e 10 b' e' 31 U Z 3 4 i 5 back to battery,

the circuit being likewise maintained open, as before described. If coin-guides a' a^2 are to be used—that is to say, if the vending price is twenty cents, a ten-cent piece for 5 each guide—switch X will be moved to H and switch Z to T. If the vending price is twenty-five cents, guides a' a^2 being used, switch X is placed on G and switch Z on T. If the vending price is to be thirty cents, switch X 10 is placed on H and Z on S. If said price is to be thirty-five cents, X will be on G and Z on S; if forty cents, X will be on H and Z on R; if forty-five cents, X will be on G and Z on H; if fifty cents, X will be on M and Z on 15 Q, current then flowing from battery h via 1 X M 25 b^5 e^5 35 O Z 3 4 i 5 back to battery. If the vending price is to be fifty-five cents, switch W is placed on E, switch X on G, and switch Z on Q. Current then flows from battery 20 h via 1 X G 20 b e 2 W E 45 M 25 b^5 e^5 35 Q Z 3 4 i 5 back to battery; if sixty cents, X is placed on L and Z on Q; if sixty-five cents, W is placed on D, X on G, and Z on Q; if seventy cents, X is placed on K and 25 Z on Q, and so on. If the vending price is one dollar, X is placed on N and Z on P. If said price is one dollar and five cents, W is placed on F, X on G, and Z on P, current 30 then flowing from battery h via 1 X G 20 b e 2 W F 46 N 26 b^6 e^6 36 P Z 3 4 i 5 back to battery. If the vending price is to be one dollar and ten cents, X is placed on L, Y on O, and Z on P; if one dollar and fifteen cents, X is placed on G, W on D, Y on O, and Z on 35 P, current then flowing from battery h via 1 X 20 b e 2 W D 44 L 24 b^4 e^4 14 55 27 O Y 28 56 b^6 e^6 36 P Z 3 4 i 5 back to battery. If the vending price is one dollar and fifty cents, X is placed on M and Z on P; if one dollar 40 and fifty-five cents, X is placed on G, W on E, and Z on P; if one dollar and sixty cents, X is placed on L and Z on P; if one dollar and sixty-five cents, W is placed on D, X on G, and Z on P; if one dollar and ninety-five cents, X is placed on G and Z on P. 45

From the above description the current in each case can be readily traced, it being of course understood that at each closure of the circuit by a coin or coins said circuit is maintained closed through contact n and the described connections with battery h through electromagnet i and will remain so closed until the coin or coins open the same by dropping on circuit-breaker g, as hereinbefore described.

By means of the described arrangement the spring-contacts b b' b^2 , &c., are so connected that the pairs of contacts closed by several coins introduced into several guides 60 are successively included in the electric circuit.

The number and value of the coins, or, in other words, the number and value of the various coin-guides, can of course be varied almost *ad libitum*, and instead of using a reciprocating cut-off slide a rotary or a vibratory cut-off may be used and without chang-

ing the operation of the apparatus or the nature of my invention.

It will furthermore be evident to any electrician that the movement of the cut-off slide to clear the coin exit or exits in the coin guide or guides may be sufficiently amplified and the coin-slots therein made of sufficient length to afford the necessary time for the coin or 75 coins to drop into chute m before the spring o can retract the slide and jam such coin or coins in the coin-exit or coin-exits. This, however, would require a greater space, and in a machine having a great number of coin-guides the slide would have to be of comparatively great length, and the accuracy of its movements might thereby be endangered.

Having thus described my invention, what I claim as new therein, and desire to secure by 85 Letters Patent, is—

1. Coin-feeding devices for coin-controlled vending-machines, comprising a coin-receiving guide, a cut-off normally blocking the coin-exit in said guide, means for moving 90 said cut-off back to a normal position when moved out of it to clear said coin-exit, and an electrically-operated appliance for moving the cut-off to clear such exit; in combination with an electric circuit including the 95 cut-off-operating appliance, circuit-terminals in the path of the coin in the guide arranged to be electrically connected by said coin to close the electric circuit and thereby cause the cut-off-operating appliance to move said 100 cut-off clear of said coin-exit, and a circuit-breaker in the path of and controlled by the released coin, substantially as and for the purpose set forth.

2. Coin-feeding devices for coin-controlled vending-machines, comprising a coin-guide, a cut-off normally blocking the coin-exit in said guide, means for moving said cut-off back to a normal position when moved clear of the exit, an electrically-controlled appliance for moving such cut-off clear of such exit, an electric circuit including said appliance, and circuit-terminals in the path of the coin in the guide arranged to be electrically connected by such coin to close said circuit 115 and thereby cause the cut-off-operating appliance to move the cut-off clear of the coin-exit, and a circuit-breaker in the path of and operated by the released coin; in combination with an auxiliary circuit-closer operating to close the circuit the moment the cut-off has cleared the aforesaid coin-exit, for the purpose set forth.

3. Coin-feeding devices for coin-controlled vending-machines, comprising a plurality of 125 coin-guides, cut-off devices normally blocking the coin-exits in said guides, means for moving said devices back to a normal position when moved clear of said exits, electrically-controlled appliances for moving said 130 cut-off devices clear of said coin-exits, an electric circuit including said appliances, circuit-terminals in each coin-guide arranged to be electrically connected by the coins in

said guides, said terminals included in series in the electric circuit, and a circuit-breaker arranged to be operated by the released coin; in combination with switch devices for switching any one or more of the pairs of coin-controlled circuit-terminals out of the circuit, for the purpose set forth.

4. Coin-feeding devices for coin-controlled vending-machines, comprising a plurality of coin-guides, cut-off devices normally blocking the coin-exits in said guides, means for moving said devices back to a normal position when moved clear of said exits, electrically-controlled appliances for moving said cut-off devices clear of said coin-exits, an electric circuit including said appliances, circuit-terminals in each coin-guide arranged to be electrically connected by the coins in said guides, said terminals included in series in the electric circuit, and a circuit-breaker arranged to be operated by the released coins; in combination with switch devices for switching any one or more of the pairs of coin-controlled circuit-terminals out of the circuit, 25 and a circuit-closer operating to close the electric circuit the moment the cut-off devices have cleared the coin-exits in the coin-guides, for the purpose set forth.

5. Coin-feeding devices for coin-controlled vending-machines, comprising a plurality of coin-guides, a coin-delivery chute below the coin-exits of and common to all said guides, a cut-off slide common to and normally blocking the coin-exits of said guides between the delivery-chute and coin-exits, an electromagnet and its armature, the latter connected with and moving the slide clear of said coin-exits, and a retracting-spring for moving the slide back to a normal position; in combination with an electric circuit including the aforesaid electromagnet, a pair of circuit-terminals in each coin-guide in the path of

and arranged to be electrically connected by the coins in said guides to close the electric circuit, said terminals included in series in 45 said circuit, a circuit-breaker at the outlet of the coin-delivery chute, and switch devices for switching any one or more of the coin-controlled circuit-terminals out of circuit, for the purpose set forth.

6. Coin-feeding devices for coin-controlled vending-machines, comprising a plurality of coin-guides, a coin-delivery chute below the coin-exits of and common to all said guides, a cut-off slide common to and normally blocking the coin-exits of said guides between the delivery-chute and coin-exits, an electromagnet and its armature, the latter connected with and moving the slide clear of said coin-exits, and a retracting-spring for moving the 60 slide back to a normal position; in combination with an electric circuit including the aforesaid electromagnet, a pair of circuit-terminals in each coin-guide in the path of and arranged to be electrically connected by 65 the coins in said guides to close the electric circuit, said terminals included in series in said circuit, a circuit-closer controlled by the movements of the electromagnet-armature to close the electric circuit the moment the cut-off slide has moved clear of the aforesaid coin-exits, a circuit-breaker at the outlet of the coin-delivery chute, and switch devices for switching any one or more of the coin-controlled terminals out of the circuit, for 70 75 the purposes set forth.

In testimony that I claim the foregoing as my invention I have signed my name in presence of two subscribing witnesses.

RICHARD KANN.
